UNITED STATES PATENT OFFICE.

MALCOLM HARD, OF FLUSHING, AND WILLIAM A. BUCKBEE, OF NYACK, NEW YORK,
ASSIGNORS TO THE SUPERHEATER COMPANY, OF NEW YORK, N. Y., A CORPORATION OF DELAWARE.

INJECTOR.

Application filed March 14, 1924. Serial No. 699,165.

To all whom it may concern:

Be it known that we, MALCOLM HARD and WILLIAM A. BUCKBEE, both citizens of the United States, and residents of Flushing, county of Queens, State of New York, and Nyack, county of Rockland, and State of New York, respectively, have invented certain new and useful Improvements in Injectors, of which the following is a specification.

This invention relates to steam injectors and particularly to that type thereof that is operated by the exhaust steam from an engine. While the use of such injectors has resulted in savings of from 10 to 15% of the fuel and water consumption of the steam locomotive, their installation has necessitated the addition of a number of manual controls which, if the maximum efficiency of the injector is to be obtained, require frequent manipulation by the engine-man. Their installation has met with considerable opposition from trainmen because of the impression that these injectors are too difficult and complicated to operate, and it has been found that, in many instances, they have been operated in a wasteful and inefficient manner. This has prevented the more universal and general adoption of exhaust steam injectors as a part of the equipment of the modern steam locomotive.

It is the principal object of this invention to provide a new and improved construction by means of which the multiplicity of manually operated control valves of the exhaust steam injectors are replaced by semi-automatically operated valves, the operation of which is controlled by a single main control valve, so that slight manipulations of a single control permit the injector control valves to be set in any of the positions required by the changing conditions encountered in the operation of the engine.

This and such further objects as practicability of installation on existing equipment, sturdiness of construction and assurance of operation under all conditions, will be apparent to those skilled in the art to which this invention appertains by reference to the following specification and to the accompanying drawings forming a part here-

of, showing in an illustrative but not in a limiting sense an embodiment of our invention.

In the drawings Fig. 1 is a side elevation showing somewhat diagrammatically an installation of an exhaust steam injector, embodying our invention, on a steam locomotive, a portion of the locomotive being shown in dotted lines.

Fig. 2 is a front elevation of the main control valve with the automatic valve attached thereto.

Figs. 3 and 4 are side and top views respectively of the structure shown in Fig. 2.

Fig. 5 is a section on the line 5—5 of Fig. 6.

Fig. 6 is a section on the line 6—6 of Fig. 4.

Fig. 7 is a section on the line 7—7 of Fig. 6.

Fig. 8 is a detail front view of the main control valve casing with the front portion thereof removed, to show clearly the steam ports and conduits of said valve casing.

Figs. 9 to 12 inclusive are detail sections of the main control valve casing taken on the line 6—6 of Fig. 4 and showing different positions of the main control valve with respect to the ports of the valve casing.

Fig. 13 is an elevation of the main control valve as seen from the side thereof which engages the valve seat of the main control valve casing.

Fig. 14 is a central vertical section through the duplex valve.

Figs. 15 and 16 are sections on the lines 15—15 and 16—16 of Fig. 14.

Fig. 17 is a central, vertical, longitudinal section through the injector.

Fig. 18 is a top view, partly in section, of the injector.

Fig. 19 is a section on the line 19—19 of Fig. 18.

Fig. 20 is a sectional detail of the injector showing the conduits leading to the exhaust steam valve operating piston, and the conduits for the auxiliary and supplementary live steam.

Referring to Figs. 1 and 17 of the drawing a preferred installation of an exhaust steam injector in accordance with the principle

5 ples of our invention consists of the following principal parts, which will be herein-
after more specifically described under the following headings: the exhaust steam injector A, equipped with the exhaust steam valve operating means B and the water admission valve C; the main control valve D, the duplex valve E, and the automatic valve F.

10 *The exhaust steam injector A.*

The exhaust steam injector shown in Figs. 17 to 20 of the drawing, which is of the type disclosed in United States Patent No. 15 1,342,128, granted June 1, 1920 to J. Metcalfe, et al., is provided with a main exhaust steam nozzle 25; a water cone or preliminary mixing nozzle 26 into which the water issues with the exhaust steam from the main exhaust steam nozzle; a combining nozzle 27; a delivery nozzle 28; a further preliminary mixing nozzle 29 between the water cone 26 and the combining nozzle 27, and a supplementary live steam nozzle 30. Exhaust steam 20 from the engine is led to the exhaust steam chamber 31 of the injector by the pipe 32, and in the form shown, an exhaust steam valve 33 is pivotally suspended within the chamber 31, adjacent to the connection of the pipe 32 to the injector, by means of the link 34, the lower end of which link is secured to the valve, by means of the bolt 35 and the upper end thereof is pivotally mounted on the pivot pin 36. A valve seat 37 is provided, against which the valve 33 is adapted to be seated to shut off communication between the pipe 32 and chamber 31.

That portion of the injector casing which defines the exhaust steam chamber 31, has 40 a web 38 projecting into said chamber from one side thereof, which web serves as a supporting means for the supplementary live steam nozzle 30, and which is also bored out to provide the steam passages 39 and 40 for 45 the supplementary and auxiliary live steam supplied through the pipes 39 and 40 respectively. In the Metcalfe type injector, the main exhaust steam nozzle 25 is mounted for movement longitudinally of the injector 50 to vary the size of the annular passage through which the water passes, between said nozzle and the water cone 26, and for this purpose a shaft 41, suitably mounted 55 for rotation upon the injector, has one end thereof adjacent to said main exhaust nozzle 25 provided with a crank pin 42 eccentrically located to the axis of said shaft and in engagement with said nozzle, whereby adjustment of the handle 41^a located in the cab, 60 and connected by the linkage 41^b will rotate said shaft and cause said nozzle 25 to be adjusted longitudinally of the injector. A one way check valve 43 is provided adjacent to the connection of the delivery pipe 43^a for 65 preventing back flow of the water from the

boiler to the injector and an automatic over-flow valve 44 (Fig. 19) is provided, which, when the injector is working, seals the over-flow chamber 45 and prevents admission of air to the injector through the overflow pipe 70 45^a. A portion of the upper half of the combining nozzle 27 is separable from the main portion thereof to form a flap 27^a which is normally seated in the position shown in Fig. 17, but which moves upwardly when 75 the pressure of the steam and (or) water within the injector exceeds a certain amount, to allow the escape of the steam and water through the comparatively large bore of the nozzle, adjacent to the nozzle 29, into the 80 overflow chamber 45. The provision of this flap ensures the prompt starting and the automatic working of the injector. The construction of the injector described above is 85 the usual construction of the Metcalfe type of exhaust steam injector and has been described herein in order that the operation of our improved control system may be more clearly understood.

90 *The exhaust steam valve operating means B.*

In place of the manually operated control means usually provided for the exhaust steam valve 33 the following means is provided:—The web 38 which extends into the 95 exhaust steam chamber 31 of the injector is extended towards the valve 33 and is bored out to provide a small cylinder 46 in which a piston 47 is slidably mounted. A piston rod 48, one end of which is suitably secured to the piston 47, has its other end projecting towards the bolt 35, with which it is adapted to engage to force the valve 33 against its seat, when the piston 47 is moved outwardly of its cylinder. Steam or other fluid under 100 pressure is admitted to the cylinder, under control of the main control valve D, through the steam passage 49, (Fig. 20), which is connected to the main control valve by the 105 pipe 50.

110 While the piston 47 is of much smaller cross sectional area than the valve 33, sufficient pressure will be exerted thereby to hold the valve to its seat because of the great difference in pressure between the live steam which acts against the piston and the exhaust steam which acts against the valve.

115 *The water admission valve C.*

The water admission valve C, (Fig. 17) 120 consists of a casing 51 in the form of an L, one branch of which is bolted to the injector A, and the other branch of which has secured thereto the water supply pipe 52 which leads to the water tank. A valve seat 53, provided in the casing 51, is adapted to be engaged by the valve 54, the stem 55 of which projects through a bearing 56, and has secured to its outer end a piston 57. The 125 piston 57 is slidably mounted within a cylin- 130

der 58 formed in the casing 52 and a small cylinder head 59, which closes the outer end of said cylinder, is provided with a screw threaded aperture 60, by means of which the pipe 61 which leads to the main control valve D is connected to the cylinder. A coiled spring 62 is mounted between the inner end of the cylinder 58 and the piston 57 and serves to hold the valve 54 normally seated upon its seat. A pipe 63, which leads from the casing of the duplex valve E, serves to conduct live steam from said casing to the casing 52 of the water admission valve C, to prevent freezing of the water in said valve or its supply pipe, or for thawing any ice which might form in said casing during freezing weather, when the injector is not in use; a valve 63^a being provided in said pipe.

20 *The main control valve D.*

The casing of the main control valve D consists of two parts, 64 and 65, bolted together by the bolts 66 (see Fig. 3). The part 65 is provided with an overhanging sector-shaped flange 67, having at the ends of the upper face thereof, the shoulders 68 and 69, (Fig. 2) and between said shoulders the notched portions 70, 71 and 72. An actuating handle 73, which is secured to the valve stem 74, is provided with a spring pressed pawl 75 adapted to engage with said shoulders and notches to serve as an indicating means for the various operative positions of the valve and to hold said valve in said positions. The inner end of the valve stem 74 is provided with a rib 76 (see Figs. 5 and 7), which engages slidably within a groove 77 formed by a pair of ribs 78 projecting from the outer face of the valve 79. The valve 79 is rotatably mounted within a valve chamber 80, formed within the casing part 65, one wall of which chamber is formed by the casing part 64. The valve body, as shown in Fig. 13 of the drawing, is provided with the through apertures which form the live steam ports 81 and 82, and the side of the valve body which engages the valve seat 85 is provided with a recess 83 consisting of a large sector 83^a and a small sector 83^b. Live steam is admitted to the valve member 80 by means of a pipe 84 which leads to the steam dome or turret of the locomotive. The inner face 85 of the casing part 64 forms the seat for the valve 79 and said face is provided with a plurality of ports 86, 87, 88, 89, and 90, (see Fig. 8) which communicate with the steam passages 91, 92, 93, 94 and 95 respectively. The port 86 and passage 91 communicate with the pipe 50 which connects the main control valve with the exhaust steam valve operating means B; the port 87 and passage 92 communicate with the pipe 61 which leads to the water ad-

sion valve C; the port 88 and passage 93 communicate with the pipe 96 which leads to the duplex valve E; and the ports 89 and 90 communicate through the passages 94 and 95 respectively with the passages 97 and 98 formed in the automatic valve F (see Fig. 6).

The recessed portion 83 of the valve 79 is in communication with a central bore 99 of the casing part 64, which bore has secured therein one end of a pipe 100 which leads to the ash pan of the locomotive and serves to permit the escape of steam from the various ports and passages of the main control lines when the main control valve 79 is actuated to bring the portion 83 thereof in alignment with said ports and passages.

The duplex valve E. (Figs. 14 to 16.)

The duplex valve E contains a pair of valve members 101 and 102 which govern the admission of the auxiliary and supplementary live steam respectively to the injector A. The casing 103 of the duplex valve E forms a shallow, substantially rectangular shaped member having at the upper end thereof a threaded nipple 104 to which is connected the pipe 105 which leads to the steam turret of the locomotive and delivers live steam to the casing 103. The pipe 105 communicates with a conduit 106 formed in the casing 103, and the valves 101 and 102 are normally held against their seats 107 and 108 respectively by the pressure of the steam within said conduits. The valve 101 is provided with a valve stem 109, which is slidably mounted within a bearing 110 formed in the casing 103, and said valve stem is connected to a piston 111 slidably mounted within a cylinder 112 formed in the casing 103. A cylinder head 113, which closes the end of the cylinder 112, is provided with a threaded aperture 114 which furnishes a means for connecting the pipe 115 thereto, said pipe leading from the automatic valve F. The valve 102 is provided with the valve stem 116, piston 117, cylinder 118, cylinder head 119 and aperture 120 of the same construction as the parts for the valve 101, but the pipe which is connected to the cylinder head 120 is the pipe 96 hereinbefore referred to which leads to the control valve D. When valve 101 is opened by the action of piston 111, live steam passes from the conduit 106 into the branched conduit 121, by which it is delivered to the auxiliary live steam pipe 40^a which leads to the injector, the path of the steam being indicated by the arrows and lines designated by the letters x in Figs. 14, 15 and 16 of the drawing. When valve 102 is opened by the action of piston 117, the live steam passes from the conduit 106 into the conduit 122, by which it is delivered to the supplementary live steam pipe 39^a which

leads to the injector, the path of the steam through the conduit 122 being indicated by the arrows and lines designated by the letters Y, in Figs. 14, 15 and 16.

5 It will be noted that the pistons 111 and 117 are sufficiently larger in area than the valves 101 and 102 respectively to insure the opening of said valves against the pressure of the steam within conduit 106 when 10 steam is admitted into the cylinders 112, 118.

Each of the valves 101 and 102 is provided with manually adjustable means, which can be set to regulate the extent of opening of said valves, and such means comprises a 15 stop rod 123 for each valve located in axial alignment with its respective valve and valve stem, but unsecured thereto. Each stop rod 123, is provided with a screw threaded portion 124 which engages with 20 cooperating screw threads formed in a screw threaded plug 125, engaged in the wall of the casing 103. Each plug 125 is provided with a stuffing box 126 through which the stop rod 123 projects, and the outer end of 25 each rod is connected by a universal joint 127 with an adjusting rod 128 provided with an operating handle 129.

A bore 130 is provided in the casing 103 for the passage of a bolt, by means of which 30 said casing is bolted to the boiler or other suitable support. It will be noted that the pipe 63 for leading steam to the water admission valve leads into the casing 103 at the base of the conduit 106. A bleed pipe 35 130^a leads from the casing of the duplex valve E to the ash pan, to withdraw any steam leakage or condensate which leaks past the pistons 111, 117 or valve stems 109, 116.

40 *The automatic valve F.*

Referring now to Figs. 2 to 6 inclusive, the casing 131 of the automatic valve F is secured to the casing part 64 of the main control valve D, by means of the bolts 132 which 45 pass through suitable apertures in the flange 133 of the casing 131. When the casing 131 is bolted to the main control valve D, as shown in Fig. 6, it will be noted that the 50 conduits or passages 97 and 98, provided in the automatic valve casing, are in alignment with the passages 94 and 95, respectively, in the main control valve D. For convenience in assembling the automatic valve to the 55 main control valve and to insure the proper alignment of the passages 97, 98, with the passages 94, 95, the face of the casing part 64 of the control valve against which the automatic valve is bolted, is provided with a circular recess 134 in which is seated a circular projection 135 provided on the automatic valve casing 131.

The passage 97 extends horizontally and 60 leads into a widened chamber 136, the upper portion of which is screw threaded to receive

a member 137 whose upper face 138 forms a valve seat for the valve 139. The valve stem 140, preferably formed integral with said valve, extends downwardly into the member 137, which member is formed with a 70 plurality of ribs 141, to provide a guide for said valve stem.

A hole 142 is drilled into the casing 131 to connect the passage 98 with its branch 143 which communicates with the pipe 115 leading to the duplex valve and which supplies the live steam for the operation of the valve 101 which controls the opening of the conduit 121 and pipe 40^a for the auxiliary steam. The hole 142 is counterbored to provide a valve chamber 146 in which the ball check valve 147 is seated to prevent the steam from the passage 97 and chamber 136 passing backwardly through the passage 98.

80 A cylinder casing 150 is screwed into the upper wall of the casing 131, the lower end of said casing 150 having a wall 151 provided with a bearing 152, in which the piston rod 153, preferably formed integral with the piston 154, is slidably mounted. The wall 90 151 is also provided with a downwardly projecting annular rib 155 which forms a valve seat for the upper face of the valve 139, and an aperture 156 leads from the bottom of the recess formed by said annular rib through 95 the wall 151 to the interior of the cylinder casing 150. A pipe 157 is screwed into the side wall of the cylinder casing 150 and connects with the pipe 100 which leads from the main control valve to the ash pan. A cylinder head 158 is screwed into the upper end of the cylinder casing 150 and is provided with a screw threaded aperture 159 in which the pipe 160 is secured. The pipe 160 leads to the main steam pipe or the steam chest of 100 the locomotive and supplies live steam to the piston 154. The piston 154 is not connected with the valve 139 but merely contacts with said valve to normally hold said valve 105 against its seat 138.

110 *Operation.*

Live steam from the turret of the locomotive is admitted through the pipe 84 into the chamber 80 of the main control valve D and 115 fills said chamber with steam under pressure. Assuming that the handle 73 of said valve is in the "off" position with the pawl 75 in engagement with the shoulder 68 of the sector shaped flange 67, the valve 79 will be 120 in the position shown in Fig. 12. In this position of the valve, it will be noted that the sector 83^a of the recess 83 will be in alignment with the ports 87 and 90 inclusive, so as to connect said ports and their communicating passages and conduits with the atmosphere through the bore 99 and pipe 100 which leads to the ash pan. The through port 81 of the valve 79 is in registry with the port 86, thus permitting the live 125 steam to pass through the valve 79.

steam from the chamber 80 of the main control valve to pass through the ports 81 and 86, to the passage 91, and thence through the pipe 50 to the injector, passing through the 5 steam passage 49 to the cylinder 46. The pressure of the live steam in cylinder 46 will force the piston 47 outwardly and by the engagement of the piston rod 48 with the bolt 35, cause the exhaust steam valve 33 to be 10 held firmly against its seat 37, thus preventing the entrance of exhaust steam to the injector.

In starting the injector, the handle 73 is moved to the position indicated by the dotted lines in Fig. 6, which corresponds to the "water on" position, the position of valve 15 79 for this position of the handle being shown in said figure. It will be noted that the port 81 is still in registry with the port 20 86 for holding the exhaust valve 33 closed, but that port 87 is now opened. The steam from the chamber 80, therefore, will pass through passage 92 to the pipe 61 which leads to the water admission valve C of the 25 injector, entering through the aperture 60 of the cylinder head 59, and forcing piston 57 and consequently valve 54 to the left (Fig. 17) against the action of the spring 62. This movement of the valve 54 obviously opens it 30 and permits the water from the water tank to flow into the injector.

The handle 73 of the main control valve is maintained momentarily in the "water on" position, until the engine-man notes an 35 escape of water from the overflow pipe 45^a. This overflow is comparatively slight as the water is only under the pressure of the head of water in the water tank and this pressure is not sufficient to open the flap 27^a of the 40 injector combining nozzle 27. As the water which fills the injector when the handle 73 is in the "water on" position is moving with a very low velocity, it is advisable in starting the injector to give it an initial or priming operation with live steam to overcome 45 the inertia of the volume of water which has now filled the injector casing. For this purpose the handle 73 and valve 79 are moved to the "priming" position shown in 50 Fig. 9, in which position the pawl 75 is engaged with the notch 71, the port 81 has moved to uncover the port 88; ports 86 and 87 still being maintained open, thereby holding the exhaust steam valve 33 closed 55 and the water valve 54 open. The opening of port 88 allows the steam to pass through the passage 93 to the pipe 96, being delivered thereby to the cylinder 118 of the duplex valve E. The live steam under pressure entering the cylinder 118 causes the piston 117 to be moved to the left, (Fig. 14), thus moving valve 102 off its seat 108 and allowing the live steam from the pipe 105 and conduit 106 to enter the conduit 60 122 and as indicated by the line Y-Y to

pass to the pipe 39^a, by which it is delivered to the steam passage 39 and supplementary live steam nozzle 30 of the injector. The live steam entering the injector through the supplementary live steam nozzle 30 raises the pressure within the injector and causes the flap 27^a to open, thus permitting a strong jet of steam and water to be discharged from the overflow pipe 45^a and setting the column of water in the injector casing in motion with a comparatively high velocity. As soon as this strong jet issues from the overflow pipe, the engine-man swings the handle 73 of the main control valve D to the next or "running" 70 75 position.

In this position of the parts, the pawl 75 is engaged with the notch 72 and the positions of the ports of the valve 79 with respect to the ports of the valve casing are 80 as shown in Fig. 10 of the drawing. The port 81 of the valve 79 has now moved from the port 86 and the sector 83^b of the recess 83 of said valve has moved into registry 85 with the port 86, thus permitting the steam 90 within the passage 91, pipe 50, steam passage 49, and cylinder 46 to escape through the recess 83 of the valve to the pipe 100 and to the ash pan. It will thus be seen that the pressure of the piston rod 48 95 against the bolt 35 will be relieved, thus permitting the exhaust steam to raise the valve 33 and flow into the injector. With the valve 79 in the position shown in Fig. 10, the ports 87, 88, and 89 of the control 100 valve casing are uncovered by the port 81; ports 87 and 88 controlling the water admission and supplementary live steam valves 54 and 102 respectively. The opening of port 89 to the live steam in the chamber 80, permits a portion of the steam 105 therein to flow through passage 94 to the passage 97 of the automatic valve F. The steam flowing through the passage 97 enters the widened portion 136, and flowing 110 through the member 137, raises the valve 139 off the valve seat 138, or fails to raise said valve off its seat, according to the pressure conditions within the pipe 160 and above the piston 154 within the cylinder 115 casing 150. It will be remembered that the pipe 160 is connected to the main steam pipe or to the steam chest of the engine, consequently if the throttle is closed no steam will be entering the main steam pipe 120 or the steam chest and therefore there will be no pressure within the pipe 160. If no steam is supplied to the engine, it is obvious that no exhaust steam will be available for operating the injector, consequently it 125 is necessary to supply live steam through the auxiliary live steam supply pipe 40^a. Assuming then, that the throttle of the locomotive is closed and the main control valve is set in the "running" position; live 130

steam from the pipe 84 will pass through the control valve D and the passages 97 and 136 of the automatic valve F and will raise valve 139 off its seat and will pass to the 5 pipe 115 by which it is led to the cylinder 112 of the duplex valve E. The pressure of the live steam in cylinder 112 will move piston 111 and valve 101 to the left, and hold the valve raised from its seat and in contact with its respective stop rod 123, thereby 10 permitting the live steam from the pipe 105 and conduit 106 to flow into the conduit 121 from which it passes to the auxiliary live steam pipe 40^a as indicated by the line 15 X—X in Figs. 14, 15 and 16. The pipe 40^a conducts the live steam to the steam passage 40 of the injector from which it enters into the exhaust steam chamber 31, through the auxiliary steam opening of the injector. 20 This live steam entering the exhaust steam chamber then flows into and through the main exhaust steam nozzle 25 and causes the jet to be established.

When the valve 139 is raised off its lower 25 seat 138 into contact with the seat formed by the lower face of the annular rib 155, the communication of the aperture 156, in the wall 151 of the automatic valve, with the passage 143 will be shut off, but when the 30 valve 139 is in its lower position, the aperture 156 is open to the passage 143 for a purpose which will hereinafter appear.

Let it now be assumed that the throttle of the engine is opened; therefore pipe 160 35 will now contain steam under pressure, and as the area of the piston 154 is considerably larger than the area of the valve 139, as clearly shown in the drawing, the pressure of the steam in pipe 160 and in the cylinder 40 casing 150 above the piston 154 will cause the valve 139 to be moved downwardly into contact with the seat 138, thus shutting off the supply of live steam from the passages 97 and 136 to the pipe 115. The steam 45 within pipe 115 and cylinder 112 is permitted to escape to the atmosphere through the aperture 156 and pipe 157 which connects with the pipe 100 leading to the ash pan. This escape of the steam from the 50 cylinder 112 will permit valve 101 to be closed by the pressure of the steam in the conduit 106 thus shutting off the supply of auxiliary live steam to the injector.

Under certain conditions, as for example 55 when the locomotive is drifting, or when it is starting from rest with a heavy train, it is desirable to operate the injector as a live steam injector even though a supply of exhaust steam is available, and this is provided for by the "emergency" position of the handle 73 and valve 79 shown in Fig. 60 11. In this position, the pawl 75 is engaged with shoulder 69, the port 81 has uncovered the ports 87, 88, 89 and 90, while 65 the port 82 of the valve 79 has uncovered

the port 86, all of the ports of the valve casing thus being opened to the steam in the valve chamber 80. The opening of the port 86, it will be remembered, causes the exhaust steam valve 33 of the injector to 70 be closed, the opening of the port 87 holds the water admission valve 54 open, the opening of the port 88 holds the supplementary live steam valve 102 open and the opening of the port 89 allows the steam to enter 75 the passage 97 of the automatic valve. The port 90 of the control valve being opened, however, allows the steam to flow through the passage 95 of the control valve to the passage 98 of the automatic valve, thus 80 raising the ball valve 147 and allowing the steam to flow through the passage 143, and thus supplying the steam to the pipe 115 irrespective of the position of the valve 139 and consequently irrespective of the pressure of the steam in the pipe 160 and cylinder casing 150. The supply of steam through the pipe 115 holding valve 101 open will permit the auxiliary live steam to enter 85 chamber 31 of the injector as heretofore 90 described. As the aperture 156 is quite small, the amount of steam which will escape therethrough is practically negligible and does not have any appreciable effect upon the pressure within the passage 143 and the 95 cylinder 112.

When the handle 73 and valve 79 are returned to the "off" position, the steam in the passages controlled by the ports 87 to 100 90 inclusive is allowed to escape to the atmosphere through the recess 83 and pipe 100 which leads to the ash pan, thus permitting the water admission valve 54 to close under the influence of the spring 62; the supplementary steam valve 102, and auxiliary steam valve 101, to be closed by the pressure of the steam in the conduit 106; and the ball valve 147 to return to its seat.

The stop rods 123 which govern the extent of the opening of the valves 101 and 110 102 may be adjusted whenever necessary by the handles 129 which are conveniently accessible in the cab, although in practice it is found that it is not ordinarily necessary to change the adjustment thereof after they 115 have once been set.

While the various valves of our control system have been described as operated by steam, it will be understood that the principles herein described are not limited to 120 steam operation but that air, water or other fluid, or electricity may be used to actuate the various valves.

It will also be understood that while our 125 invention is illustrated, for the purposes of this application, as applied to the Metcalfe type of injector, the principles herein disclosed are applicable to various types of injectors, and also that the constructional details of the various valve members and the 130

location thereof in the system may obviously be varied as desired without departing from the spirit of our invention.

Having thus disclosed our invention, we declare that what we claim as novel and desire to secure by Letters Patent of the United States is:

1. The combination with an exhaust steam injector having a plurality of valve controlled supply lines, of a single main control valve to govern the actuation of the valves of said supply lines, said main control valve located at a point removed from said injector, means for actuating the valves in said supply lines, and connections from said main control valve to said means.

2. The combination with an exhaust steam injector having a plurality of valve controlled supply lines, of fluid pressure operated means to actuate the valves in said supply lines, a main control valve to govern the actuation of said fluid pressure means, and connections between said fluid pressure operated means and main control valve.

25 3. The combination with an exhaust steam injector having a plurality of valve controlled supply lines, of fluid pressure operated means to actuate the valves in said supply lines, a main control valve located at a point remote from said injector, and connections between said main control valve and said injector.

35 4. In an exhaust steam injector having a plurality of supply lines, a valve to control each of said supply lines, fluid pressure operated means to actuate each of said valves, a main control valve located at a point remote from said injector, connections from said main control valve to said fluid pressure operating means, a single manually operable handle and means actuated thereby to control the admission of fluid under pressure to all of said connections.

45 5. In an exhaust steam injector having a plurality of inlets, supply lines connected with said inlets, a valve in each of said supply lines, fluid pressure operated means to actuate said valves, a main control valve comprising a casing having a plurality of ports therein, a single valve to control the opening of said ports mounted within said casing and connections from said ports to said fluid pressure means to permit the valves in said supply lines to be controlled by the actuation of said single valve.

55 6. In an exhaust steam injector, a plurality of valve controlled supply conduits, means to actuate the valves in each of said supply lines and a single unitary control to govern the actuation of said means.

60 7. In an exhaust steam injector having a plurality of supply conduits connected therewith, a valve for each of said conduits, fluid pressure actuating means for the

valves of said conduits, a main control valve 65 casing, having a plurality of ports, a main control valve within said casing, means to supply fluid under pressure to said casing, connections from said ports to said fluid pressure actuating means, and said main control valve having a plurality of ports constructed and arranged to admit the fluid under pressure to said connections and fluid pressure actuating means when said valve is in a certain predetermined position. 70 75

8. In an exhaust steam injector having a plurality of supply conduits connected therewith, a valve for each of said conduits, fluid pressure actuating means for the valves of said conduits, a main control valve casing, having a plurality of ports, a main control valve within said casing, means to supply fluid under pressure to said casing, connections from said ports to said fluid pressure actuating means, said 80 main control valve being provided with a plurality of pressure and exhaust ports, said pressure ports being adapted when aligned with the ports of said casing to permit a supply of fluid under pressure to flow 85 through the ports of said casing to said connections, and said exhaust ports when aligned with said casing ports permitting the escape of said fluid from said connections and fluid pressure actuating means. 90 95

9. In an exhaust steam injector having a plurality of supply conduits connected therewith, a valve for each of said conduits, fluid pressure actuating means for the valves of said conduits, a main control valve casing, having a plurality of spaced ports, a main control valve within said casing, means to supply fluid under pressure to said casing, connections from said ports to said fluid pressure actuating means, said 100 main control valve being provided with a plurality of pressure ports spaced equally to the ports of said valve casing and adapted to be brought in alignment therewith and permit the fluid under pressure within said casing to flow to said connections and fluid pressure actuating means, and said main control valve having a plurality of spaced exhaust ports adapted when brought into alignment with the ports of said valve casing to permit the pressure of the fluid within 105 said connections and actuating means to be relieved. 110 115

10. In an exhaust steam injector having a plurality of supply conduits connected therewith, a valve for each of said supply conduits, fluid pressure actuating means for the valves of said conduits, a main control valve casing having a plurality of spaced ports, connections communicating with and leading from said ports to said fluid pressure actuating means, means to supply a fluid under pressure to said valve casing, 120 125

an exhaust pipe connected to said valve casing, a main control valve movably mounted within said valve casing, said main control valve being provided with a plurality of spaced pressure ports and a plurality of spaced exhaust ports, said pressure ports constructed and arranged to permit the fluid from said valve casing, when any one of said pressure ports is brought into alignment with a port of said valve casing, to flow to the respective connection and fluid pressure actuating means for said valve casing port; and said exhaust ports being constructed and arranged to connect the remainder of said valve casing ports with said exhaust pipe and vent the connections to said ports to the atmosphere.

11. In an exhaust steam injector having a plurality of supply conduits connected therewith, a valve for each of said conduits, fluid pressure actuating means for the valves of said conduits, a main control valve casing having a plurality of ports, means to supply a fluid under pressure to said valve casing, a main control valve movably mounted within said casing, connections from the ports of said casing to said fluid pressure means, and said main control valve provided with a plurality of ports constructed and arranged to be brought into alignment with different ports of said valve casing when said valve is moved to different adjusted positions.

12. In an exhaust steam injector, a conduit connected therewith and leading to the supply of exhaust steam from an engine, a valve for closing said conduit, and a pressure responsive element for closing said valve against the pressure of the exhaust steam within said conduit.

13. In an exhaust steam injector, a conduit connected therewith and leading to a supply of exhaust steam from an engine, a valve for closing said conduit, a pressure responsive element for closing said valve against the pressure of the exhaust steam within said conduit and a control device located at a point remote from said injector for controlling the operation of said pressure element.

14. In an exhaust steam injector, a conduit connected therewith and leading to a supply of exhaust steam from an engine, a valve for closing said conduit, and fluid pressure means for closing said valve against the pressure of the exhaust steam within said conduit.

15. In an exhaust steam injector, a conduit connected therewith and leading to a supply of exhaust steam from an engine, a valve for closing said conduit and fluid pressure means located within said injector for closing said valve against the pressure of the exhaust steam within said conduit.

16. In an exhaust steam injector, a conduit connected therewith and leading to a supply of exhaust steam from an engine, a valve for closing said conduit, a cylinder and piston for closing said valve against the pressure of the exhaust steam within said conduit and means for supplying fluid under pressure to said cylinder and piston.

17. In an exhaust steam injector, a conduit connected therewith and leading to a supply of exhaust steam from an engine, a valve for closing said conduit, a cylinder and piston for closing said valve against the pressure of the exhaust steam within said conduit and means for supplying fluid under pressure to said cylinder and piston, including control means located at a point remote from said injector to govern the supply of fluid to said cylinder and piston.

18. In an exhaust steam injector, a conduit connected therewith and leading to a supply of exhaust steam from an engine, a valve for closing said conduit, and means located within said injector to close said valve against the pressure of the exhaust steam within said conduit.

19. In an exhaust steam injector, a conduit connected therewith and leading to a supply of exhaust steam from an engine, a valve for closing said conduit, a cylinder and piston within said injector, a piston rod connected with said piston and cooperatively associated with said valve, and means to supply a fluid under pressure to said cylinder and piston to close said valve against the pressure of the exhaust steam within said conduit, said means including a controlling device located at a point remote from said injector to govern the supply of fluid to said cylinder and piston.

20. An exhaust steam injector having an exhaust steam chamber, a conduit furnishing communication between said exhaust steam chamber and the exhaust steam line of an engine, a valve for closing said conduit, a web projecting into the interior of said exhaust steam chamber, said web being provided with a cylinder and a passage communicating with said cylinder, a piston slidably mounted within said cylinder, a piston rod connected with said piston adapted to engage said valve, and means to supply fluid under pressure to said cylinder and piston to cause said valve to be closed against the pressure of the exhaust steam within said conduit.

21. An exhaust steam injector, having a conduit connected therewith and leading to a supply of exhaust steam from an engine, a valve for closing said conduit, movably mounted adjacent to the connection of said conduit to said injector and movable to opened position by the pressure of the exhaust steam within said conduit, and fluid

pressure operated means adjacent to said valve to close said valve against the pressure of said exhaust steam.

22. In an exhaust steam injector, a conduit secured thereto and leading to a supply of water, a valve for closing said conduit, means to normally hold said valve in closed position, and pressure means cooperatively associated with said valve to move it to 10 opened position.

23. In an exhaust steam injector, a conduit secured thereto and leading to a supply of water, a valve for closing said conduit, means to normally hold said valve in 15 closed position, and fluid pressure operated means cooperatively associated with said valve to move it to opened position.

24. In an exhaust steam injector, a conduit secured thereto and leading to a supply 20 of water, a valve for closing said conduit, means to normally hold said valve in closed position, and fluid pressure operated means cooperatively associated with said valve to move it to opened position, and a control 25 valve located at a point remote from said injector to govern the supply of fluid under pressure to said fluid pressure operated means.

25. In an exhaust steam injector, a conduit secured thereto and leading to a supply 30 of water, a valve for closing said conduit, means to normally hold said valve in closed position, a cylinder and piston adjacent to said valve and cooperatively associated therewith, and means to supply fluid 35 under pressure to said cylinder and piston.

26. In an exhaust steam injector, a conduit secured thereto and leading to a supply 40 of water, a valve for closing said conduit, means to normally hold said valve in closed position, a cylinder and piston adjacent to said valve and cooperatively associated therewith, and means to supply fluid under pressure to said cylinder and piston, including means to control the admission of 45 said fluid to said cylinder and piston.

27. In an exhaust steam injector, a conduit secured thereto and leading to a supply 50 of water, a valve for closing said conduit, means to normally hold said valve in closed position, a cylinder and piston adjacent to said valve and cooperatively associated therewith, and means to supply a fluid under pressure to said cylinder and piston including a control valve located at a point 55 remote from said injector.

28. In an exhaust steam injector, a conduit secured thereto and leading to a supply 60 of water, a valve for closing said conduit, means to normally hold said valve in closed position, fluid pressure operated means cooperatively associated with said valve to move it to opened position, and means to supply heat to said water supply conduit 65 and said valve and associated parts.

29. In an exhaust steam injector having conduits connected therewith for supplying exhaust steam, supplementary live steam and auxiliary live steam to said injector, valves located in the supplementary live 70 steam and the auxiliary live steam conduits, and fluid pressure operated means to actuate said valves.

30. In an exhaust steam injector having conduits connected therewith for supplying exhaust steam, supplementary live steam and auxiliary live steam to said injector, valves located in the supplementary live 75 steam and the auxiliary live steam conduits, said valves constructed and arranged to be 80 closed by the pressure of the steam flowing to said live steam conduits, and fluid pressure means to open said valves against the pressure of said steam.

31. In an exhaust steam injector having 85 conduits connected therewith for supplying exhaust steam, supplementary live steam and auxiliary live steam to said injector, valves located in the supplementary live steam and the auxiliary live steam conduits, said valves 90 constructed and arranged to be closed by the pressure of the steam flowing to said live steam conduits, fluid pressure means to open said valves, against the pressure of said steam, and adjustable stop means to control 95 the extent of opening of said valves.

32. In an exhaust steam injector having a conduit connected therewith for supplying exhaust steam from an engine to said injector; a valve casing having a main live steam 100 conduit therein adapted to be connected to a source of live steam, and a pair of branch conduits in communication with said main live steam conduit; said branch conduits being connected with said injector to supply 105 supplementary and auxiliary live steam thereto, a valve for controlling the communication between said main conduit and each of said branch conduits and fluid pressure operated means to actuate each of said 110 valves.

33. In an exhaust steam injector having conduits connected therewith for supplying exhaust steam, supplementary live steam and auxiliary live steam to said injector, 115 valves located in the supplementary live steam and the auxiliary live steam conduits, fluid pressure operated means to actuate said valves and control means located at a point remote from said fluid pressure means to 120 govern the actuation thereof.

34. In an exhaust steam injector having a plurality of conduits connected therewith for supplying exhaust steam, supplementary live steam and auxiliary live steam to said 125 injector, a valve casing having a main live steam conduit therein adapted to be connected to a source of live steam and a pair of branch conduits in communication with said main live steam conduit for conducting 130

- the live steam to said supplementary and auxiliary live steam conduits, a pair of valves one for each of said branch conduits adapted to be moved to closed position by the pressure of the steam within said main live steam conduit, a cylinder for each of said valves formed within said valve casing, a piston within each of said cylinders cooperatively associated with its respective valve, means to supply a fluid under pressure to said cylinder and pistons to cause said valves to be moved to opened positions against the pressure of the steam within said main live steam conduit.
35. In an exhaust steam injector having a plurality of conduits connected therewith for supplying exhaust steam, supplementary live steam and auxiliary live steam to said injector, a valve casing having a main live steam conduit therein adapted to be connected to a source of live steam and a pair of branch conduits in communication with said main live steam conduit for conducting the live steam to said supplementary and auxiliary live steam conduits, a pair of valves one for each of said branch conduits adapted to be moved to closed position by the pressure of the steam within said main live steam conduit, a cylinder for each of said valves formed within said valve casing, a piston within each of said cylinders cooperatively associated with its respective valve, means to supply a fluid under pressure to said cylinders and pistons to cause said valves to be moved to opened positions against the pressure of the steam within said main live steam conduit, including a control valve located at a point remote from said injector.
40. In an exhaust steam injector having a plurality of conduits connected therewith for supplying exhaust steam, supplementary live steam and auxiliary live steam to said injector, a valve casing having a main live steam conduit therein adapted to be connected to a source of live steam and a pair of branch conduits in communication with said main live steam conduit for conducting the live steam to said supplementary and auxiliary live steam conduits, a pair of valves one for each of said branch conduits adapted to be moved to closed position by the pressure of the steam within said main live steam conduit, a cylinder for each of said valves formed within said valve casing, a piston within each of said cylinders cooperatively associated with its respective valve, means to supply a fluid under pressure to said cylinders and pistons to cause said valves to be moved to open positions against the pressure of the steam within said main live steam conduit, including a control valve located at a point remote from said injector and having separate ports and connections therefrom leading to said cylinders to permit said pistons and valves to be selectively actuated.
37. The combination with an exhaust steam injector having conduits connected therewith for supplying exhaust steam from an engine, supplementary live steam and auxiliary live steam to said injector, of a valve for each of said conduits, fluid pressure operated means for actuating said valves, a main control valve and connections therefrom to said fluid pressure means, for controlling the admission of fluid to said fluid pressure means, and means interposed in the connection between said control valve and the fluid pressure means for said auxiliary live steam conduit for automatically preventing the flow of fluid to said last mentioned fluid pressure means when said engine is performing work.
38. The combination with an exhaust steam injector having connected therewith a conduit leading to the exhaust steam line of an engine, and a conduit for supplying auxiliary live steam to said injector, of a valve for controlling the flow of steam through said auxiliary live steam conduit, a fluid pressure actuated means for operating said valve, a main control valve and connections therefrom to said fluid pressure means and means interposed in the connection from said control valve to said fluid pressure actuated means for preventing operation of said fluid pressure means when said engine is performing work, said means comprising a valve member, a cylinder connected with the live steam supply to said engine, and a piston in said cylinder cooperatively associated with said valve member.
39. The combination with an exhaust steam injector having connected therewith a conduit leading to the exhaust steam line of an engine, and a conduit for supplying auxiliary live steam to said injector, of a valve for controlling the flow of steam through said auxiliary live steam conduit, a fluid pressure actuated means for operating said valve, a main control valve and connections therefrom to said fluid pressure means and means interposed in the connection from said control valve to said fluid pressure actuated means for preventing operation of said fluid pressure means when said engine is performing work, said means comprising a valve member, a cylinder connected with the live steam supply to said engine, and a piston in said cylinder cooperatively associated with said valve member, and means governed by said main control valve to by-pass the fluid under pressure around said valve member when said main control valve is set in a predetermined position.
40. The combination with an exhaust steam injector having connected therewith a conduit leading to the exhaust steam line

of an engine, and a conduit for supplying auxiliary live steam to said injector, of a valve for controlling the flow of steam through said auxiliary live steam conduit, opening said valve and means to prevent 65 automatically the operation of said fluid pressure means when exhaust steam is being supplied to said injector.

- 5 a fluid pressure actuated means for operating said valve, a main control valve and connections therefrom to said fluid pressure means and means interposed in the connection from said control valve to said fluid 10 pressure actuated means for preventing operation of said fluid pressure means when said engine is performing work, said means comprising a valve member, a pressure responsive member connected with the live 15 steam supply to said engine and cooperatively associated with said valve member, and a by-pass conduit to allow the fluid to flow to said fluid pressure actuated means irrespective of the position of said valve 20 member, when said control valve is set in a predetermined position.

41. The combination with an exhaust steam injector having connected therewith a conduit leading to the exhaust steam line 25 of an engine, and a conduit for supplying auxiliary live steam to said injector, of a valve for controlling the flow of steam through said auxiliary live steam conduit, a fluid pressure actuated means for operating 30 said valve, a main control valve and connections therefrom to said fluid pressure means and means interposed in the connection from said control valve to said fluid pressure actuated means for preventing 35 operation of said fluid pressure means when said engine is performing work, said means comprising a valve member, a cylinder connected with the live steam supply to said engine, and a piston in said cylinder 40 operatively associated with said valve member, a by-pass conduit operatively connected with said main control valve, and a one-way valve located within said by-pass conduit to prevent fluid passing from said control valve 45 through said valve member from flowing through said by-pass conduit to said main control valve.

42. In an exhaust steam injector having a conduit connected therewith for supplying exhaust steam from an engine to said injector, a second conduit connected with said injector for supplying auxiliary live steam thereto, a valve to control the flow of steam to said second conduit, and means to prevent automatically the opening of said valve when exhaust steam is being supplied to said exhaust steam conduit.

43. In an exhaust steam injector having a conduit connected therewith for supplying exhaust steam from an engine to said injector, a second conduit connected with said injector for supplying auxiliary live steam thereto, a valve for said second conduit, fluid pressure actuated means for 50

opening said valve and means to prevent 65 automatically the operation of said fluid pressure means when exhaust steam is being supplied to said injector.

44. In an exhaust steam injector having a conduit connected therewith for supplying exhaust steam from an engine to said injector, a second conduit connected with said injector for supplying auxiliary live steam thereto, a valve for said second conduit, fluid pressure actuated means for opening 70 said valve, a main control valve for governing admission of fluid to said fluid pressure means, and means interposed between said main control valve and fluid pressure means to prevent automatically the 75 actuation of said fluid pressure means when exhaust steam is being supplied to said injector.

45. In an exhaust steam injector having a conduit connected therewith for supplying exhaust steam from an engine to said injector, a second conduit connected with said injector for supplying auxiliary live steam thereto, a valve for said second conduit, fluid pressure actuated means for opening 80 said valve, an automatic valve for governing the supply of fluid under pressure to said fluid pressure means, a pressure responsive member cooperatively associated with said automatic valve and means connecting said pressure responsive member with the main live steam supply of said engine to cause said pressure responsive member to prevent said automatic valve from 85 opening when live steam under pressure is 90 flowing to said engine.

46. In an exhaust steam injector having a conduit connected therewith for supplying exhaust steam from an engine to said injector, a second conduit connected with 105 said injector for supplying auxiliary live steam thereto, a valve for said second conduit, fluid pressure actuated means for opening said valve, a main control valve for controlling the supply of fluid to said fluid pressure means, a freely mounted valve interposed between said main control valve and said fluid pressure means, a pressure responsive member cooperatively associated with said freely mounted valve, and connections between said pressure responsive member and the main steam supply line to the engine to prevent said freely mounted valve from opening when live steam under 110 pressure is being supplied to said engine.

47. In an exhaust steam injector having a conduit connected therewith for supplying exhaust steam from an engine to said injector, a second conduit connected with said injector for supplying auxiliary live steam thereto, a valve for said second conduit, fluid pressure actuated means for opening said valve, a main control valve, connections there- 115 120 125

from to said fluid pressure actuated means, a valve casing interposed within said connections, a freely floating valve mounted within said valve casing adapted normally to be raised off its seat by the pressure of the fluid flowing to said fluid pressure means, a pressure responsive member cooperatively associated with said valve and connections from said pressure responsive member to the main steam supply line of the engine to cause said pressure responsive member to hold said freely floating valve on its seat when live steam under pressure is being supplied to said engine.

48. In an exhaust steam injector having a conduit connected therewith for supplying exhaust steam from an engine to said injector, a second conduit connected with said injector for supplying auxiliary live steam thereto, a valve for said second conduit, fluid pressure actuated means for opening said valve, a main control valve, connections therefrom to said fluid pressure actuated means, a valve casing interposed within said connections, a freely floating valve mounted within said valve casing adapted normally to be raised off its seat by the pressure of the fluid flowing to said fluid pressure means, a pressure responsive member cooperatively associated with said valve and connections from said pressure responsive member to the main steam supply line of the engine to cause said pressure responsive member to hold said freely floating valve on its seat when live steam under pressure is being supplied to said engine, and a by-pass conduit within said valve casing controlled by said main control valve to permit the fluid under pressure to be by-passed about said freely floating valve irrespective of its position when said control valve is set to open said by-pass conduit.

49. The combination with an exhaust steam injector having a conduit connected therewith leading from a supply of exhaust steam from an engine, and a second conduit for supplying auxiliary live steam to said injector, of a normally closed valve for controlling the flow of live steam to said second conduit, fluid pressure actuated means for opening said valve, a main control valve and connections therefrom to said fluid pressure actuated means, and means within said connections to permit the escape of the fluid under pressure from said fluid pressure means and said connections and thereby permit said fluid pressure means to allow said valve to close.

50. The combination with an exhaust steam injector having a conduit connected therewith leading from a supply of exhaust steam from an engine and a second conduit for supplying auxiliary live steam to said injector, of a normally closed valve for con-

trolling the flow of live steam to said second conduit, fluid pressure actuated means for opening said valve, a pipe leading from said fluid pressure means, a valve casing having a pair of conduits therein communicating with said pipe, a main control valve controlling the admission of fluid under pressure to said pair of conduits, one of the members of said pair of conduits being provided with a freely floating valve and the other of the members of said pair of conduits having a one way valve therein to prevent the fluid which passes through said first named member from flowing to said control valve.

51. The combination with an exhaust steam injector having a conduit connected therewith leading from a supply of exhaust steam from an engine and a second conduit for supplying auxiliary live steam to said injector, of a normally closed valve for controlling the flow of live steam to said second conduit, fluid pressure actuated means for opening said valve, a pipe leading from said fluid pressure means, a valve casing having a pair of conduits therein communicating with said pipe, a main control valve controlling the admission of fluid under pressure to said pair of conduits, one of the members of said pair of conduits being provided with a freely floating valve and the other of the members of said pair of conduits having a one way valve therein to prevent the fluid which passes through said first named member from flowing to said control valve, and a pressure responsive member within said valve casing in communication with the main steam supply line of the engine to hold said freely floating valve on its seat and prevent fluid under pressure from passing to said pipe when live steam under pressure is flowing to said engine.

52. The combination with an exhaust steam injector having a conduit connected therewith leading from a supply of exhaust steam from an engine and a second conduit for supplying auxiliary live steam to said injector, of a normally closed valve for controlling the flow of live steam to said second conduit, fluid pressure actuated means for opening said valve, a pipe leading from said fluid pressure means, a valve casing having a pair of conduits therein communicating with said pipe, a main control valve for controlling the admission of fluid under pressure to said pair of conduits, one of the members of said pair of conduits having a valve member and a pressure responsive control therefor automatically to hold said valve member closed when exhaust steam under pressure is being supplied to the injector and the other member of said pair of conduits providing a by-pass to permit the fluid under pressure to flow to said pipe and fluid pressure actuating means irrespective of the

position of said valve member and the pressure of the exhaust steam flowing to said injector.

53. In an exhaust steam injector, an exhaust steam conduit connected therewith for supplying exhaust steam from an engine to said injector, a conduit for supplying water to said injector, a valve for said exhaust steam conduit, adapted to be moved to an opened position by the pressure of the steam within said exhaust steam conduit, a valve within said water conduit, means to hold said last named valve normally in closed position, fluid pressure means for each of said valves to close the exhaust steam valve against the pressure of the exhaust steam and to open the water valve and a control device located at a point remote from said injector for controlling the actuation of said fluid pressure means.

54. In an exhaust steam injector, an exhaust steam conduit, a water conduit and a supplementary live steam conduit connected with said injector, a valve for each of said conduits, fluid pressure actuated means for actuating each of said valves and a main control valve for selectively controlling the operation of each of said fluid pressure actuated means.

55. In an exhaust steam injector, an exhaust steam conduit, a water conduit, a supplementary live steam conduit and an auxiliary live steam conduit connected with said injector, a valve for controlling each of said conduits, a fluid pressure actuated means for operating each of said valves and a single main control valve for controlling the operation of each fluid pressure actuated means.

56. In an exhaust steam injector, an exhaust steam conduit, a water conduit, a supplementary live steam conduit and an auxiliary live steam conduit connected with said injector, a duplex valve containing a pair of valves for controlling the admission of live steam to said supplementary and auxiliary live steam conduits, a valve for said exhaust steam conduit, a valve for said water conduit, fluid pressure actuated means for operating all of said valves, and a single control valve and connections therefrom to the fluid pressure actuated means for each of said valves for controlling the operation of said valves.

57. In an exhaust steam injector, an exhaust steam conduit, a water conduit, a supplementary live steam conduit and an auxiliary live steam conduit connected with said injector, a duplex valve containing a pair of valves for controlling the admission of live steam to said supplementary and auxiliary live steam conduits, a valve for said exhaust steam conduit, a valve for said water conduit, fluid pressure actuated means for op-

erating all of said valves, and a single control valve and connections therefrom to the fluid pressure actuated means for each of said valves for controlling the operation of said valves, said single control valve adapted to be set in a plurality of predetermined positions in which fluid under pressure will be supplied to certain of said fluid pressure actuated means and not to others of said fluid pressure actuated means.

58. In an exhaust steam injector, an exhaust steam conduit, a water conduit, a supplementary live steam conduit and an auxiliary live steam conduit connected with said injector, a duplex valve containing a pair of valves for controlling the admission of live steam to said supplementary and auxiliary live steam conduits, a valve for said exhaust steam conduit, a valve for said water conduit, fluid pressure actuated means for operating all of said valves, and a single control valve and connections therefrom to the fluid pressure actuated means for each of said valves for controlling the operation of said valves, said single control valve constructed and arranged when set in a certain predetermined position to admit fluid under pressure to all of said fluid pressure actuated means.

59. In an exhaust steam injector, an exhaust steam conduit, a water conduit, a supplementary live steam conduit and an auxiliary live steam conduit connected with said injector, a duplex valve containing a pair of valves for controlling the admission of live steam to said supplementary and auxiliary live steam conduits, a valve for said exhaust steam conduit, a valve for said water conduit, fluid pressure actuated means for operating all of said valves, and a single control valve and connections therefrom to the fluid pressure actuated means for each of said valves for controlling the operation of said valves, and means interposed between said control valve and the fluid pressure actuated means for the auxiliary live steam valve to prevent automatically the flow of fluid under pressure thereto when exhaust steam under pressure is flowing through said exhaust steam conduit.

60. In an exhaust steam injector, an exhaust steam conduit, a water conduit, a supplementary live steam conduit and an auxiliary live steam conduit connected with said injector, a duplex valve containing a pair of valves for controlling the admission of live steam to said supplementary and auxiliary live steam conduits, a valve for said exhaust steam conduit, a valve for said water conduit, fluid pressure actuated means for operating all of said valves, and a single control valve and connections therefrom to the fluid pressure actuated means for each of said valves for controlling the operation of

said valves, and means interposed between said control valve and the fluid pressure actuated means for the auxiliary live steam valve to prevent automatically the flow of fluid under pressure thereto when exhaust steam under pressure is flowing through said exhaust steam conduit, said last named means comprising an automatic valve and a

pressure responsive member cooperatively associated with said automatic valve and 10 connected with the live steam supply line leading to the engine.

In testimony whereof we have hereunto set our hands.

MALCOLM HARD.
WILLIAM A. BUCKBEE.
